UNITED STATES PATENT OFFICE

EDMOND ETORÉ, OF COURBEVOIE, FRANCE

MECHANISM FOR RAISING AND LOWERING SLIDING WINDOWS

Application filed October 8, 1927, Serial No. 224,844, and in France December 2, 1926.

This invention relates to mechanism for raising and lowering sliding windows, and more particularly the windows of automobiles.

5 According to one feature of this invention, the window is raised or lowered by the action communicated by a handle to a toothed wheel mounted on an axis, which wheel acts upon a rack mounted on a link and pivoted at one 10 end of the lever supporting the window, which communicates to the lever, and in consequence to the window, an upward or downward movement, according to the direction in which the handle is turned.

15 The invention is illustrated in the accompanying drawings, as applied to the window formed in the door of an automobile, and Figure 1 is a front view of the apparatus mounted on the window, viewed from the 20 interior; Figure 2 is a section of the apparatus indicating its position and method of fixation in the door; Figure 3 is a front view of the apparatus, the outer panel of the door being removed to permit the apparatus to be 25 more clearly seen; Figure 4 shows a front view of an intermediate apparatus between the handle and the rack; Fig. 5 is an end view of Fig. 4; Figure 6 is a side view of the 30 same arrangement; Figure 7 is an underneath view; Figure 8 shows another intermediate apparatus between the handle and the rack, Figure 9 is a plan view of the same arrangement; Figure 10 is a side view of the same 35 arrangement; Figure 11 is an underneath view; Figures 12 and 13 show details of construction.

In Figure 1, the full lines show the window in its lowermost or open position; in Figure 40 3, it is shown in its closed or uppermost position, the dot and dash lines in Figure 1 showing it in an intermediate position.

The present arrangement (Figures 2 and 3) 45 comprises a plate F fixed to the frame of the door by screws, and having a fixed pin O_1 forming an axis on which a lever L is mounted.

Lever L is also provided with two pins O_2 50 and O_3 , the first of which is for the attachment of the spring R, secured at its other end to a pin O_4 on the plate F, the second pin O_3

serving as a pivot for a rack C. At the other end of the lever L is another pin O_5 adapted to engage in a slot g formed in the window frame indicated at s, which slot g at one end is provided with an enlarged hole ω , the diameter of which is greater than that of the pin O_5 .

55 The rack C is pivoted as stated above on the pin O_5 of the lever L, and is guided by a stirrup piece A, which can oscillate about a short shaft Ω on the end of which is mounted an operating handle M.

The rack C meshes with a toothed wheel r fast on the shaft Ω by means of the intermediate apparatus hereinafter described.

60 This shaft, (Figures 4, 5, 6 and 7) is provided with a head t and two screw holes V_1 and V_2 .

This shaft passes through the stirrup A and then the toothed wheel r , which is formed in one with a hub portion or sleeve having two flats m_1 and m_2 .

65 A member D, which has the form shown in Figure 6, is fitted on the hub of the toothed wheel, just above the flats. On the shaft Ω is a member E adapted to engage with the two flats m_1 and m_2 of the wheel r , and supported by an axis a fitted on the shaft Ω . There are also two springs ρ which are 70 in a symmetrical position with respect to the axis of the Figure 4; these springs lean against the rear portion of the member D and enter hollows formed in the back sides of the member E.

75 This whole apparatus is contained within a box B, screwed on the plate F, as shown in Figure 2. This box is provided in its bottom with a series of teeth circularly placed (Figure 4). On the shaft Ω is fitted a handle M, fixed by a screw V_1 , and prevented from 80 rotating by means of another screw V_2 .

85 On the Figure 3, are shown three little pins similar to the pin O_4 used for fixation of the spring, and disposed with respect to this last one, so as to be placed at the four corners of a square; they are used to control the spring during compression and expansion.

90 The window being closed, the rotative motion of the handle M in the direction of the arrow (Fig. 3) is sufficient to open it. At the 95 100

beginning of this motion, the tooth d of the member E is situated between two teeth of the bottom of the box B; it meets therefore directly one of these teeth with a fixed resistance, but the member E compresses the two springs allowing the tooth d to overcome this resistance and to cross over the next tooth.

It must be noted that, at this time, if the rotative motion were stopped, the window 10 would stay in its position, for the springs have an action which is slightly superior to the action transmitted to the lever L by the weight of the window. As soon as the tooth d is between two teeth of the box B, the system 15 stops, the spring ρ being then slightly prevailing, and the window is unable to move from the position that has been fixed to it.

During the rotative motion hereabove described, the teeth of the wheel r mesh with the 20 teeth of the rack C, and cause it to advance in the direction of the arrow. It gives the lever L by the intermediate of the pin O_3 , a rotative motion about the pin O_1 , whilst the lever L acts upon the window which is led 25 laterally, and the pin O_5 comes to a convenient position, in the slide bar. The stirrup A has obviously moved during this motion round the shaft Ω .

This invention allows therefore by a very 30 simple movement, to give the window any desired position without fear that it will move under its own weight or due to shocks.

Instead of using the intermediate apparatus between the handle and the rack, that is 35 illustrated in the Figures 1 to 7, I prefer to employ the mechanism shown in Figures 8 to 13.

The shaft Ω (Figures 4, 5, 6 and 7) is provided with a head t , and is splined as at m_3 40 and m_4 , and is provided with a screw hole V_1 to receive the handle M. This shaft passes through the stirrup A and then the toothed wheel r , which is formed in one with a hub portion or sleeve having two flats m_1 45 and m_2 .

On the shaft Ω is a member E adapted to engage with the two flats m_1 and m_2 of the wheel r , and which (Figure 13) is provided with an eccentric hole u for the passage of the 50 shaft Ω and in addition with a slot T for receiving a pin a carried by the shaft Ω .

When the member E has been placed in position (Figure 11), there is placed on its front part a frame G of arcuate form, which butts 55 against each end of the pin a . In this frame are rollers g_1 and g_2 between which is inserted a spring R_1 that is held in position by a cover piece B, secured to the plate F.

The handle M is finally mounted on the 60 head T and secured in position by a screw V_1 . The window is moved to open or close by the rotation of the handle M which causes the rotation of the toothed wheel r , in engagement with which is the rack C pivotally connected to the window supporting lever L.

The operation of the mechanism is as follows (see more particularly Figures 8 to 13). Suppose the window to have been moved to an open position where under the action of its own weight or vibration it tends to fall, rotary movement in the direction of arrow 70 (Figure 3) is transmitted by means of the rack C to the toothed wheel r , and the member E in engagement with the flats m_1 and m_2 formed on the hub portion of the wheel r .

The member E owing to it being eccentrically mounted on the shaft Ω will on rotation wedge the roller g_1 against the inner surface of the casing B, when further movement of the wheel r is prevented, and the window is 80 held fast.

On the rotation of the handle in the same direction, the pin a carried by the shaft Ω will engage the left hand end of the frame G, in which are mounted the rollers g_1 and g_2 , and the whole that is frame G and member E will rotate within the casing B, the wheel r which is connected to the member E 85 also rotating to operate the window.

It is evident that rotational movement in 90 the reverse direction will have the effect of causing the roller g_1 to wedge itself in place of the roller g_2 ; the operation is thus identical in the two directions.

The present invention thus permits, by a 95 very simple movement, without using any force, of moving the window to any desired position without fear that the latter will move under its own weight or due to shock.

It has in respect to the systems already 100 known the advantage of a very simple operation, and low cost.

Having now particularly described and ascertained the nature of my said invention, and in what manner the same is to be performed, I declare that what I claim is:

1. In a combined window regulator and locking device, a casing adapted to be secured to the window support, a shaft journaled in the casing, a handle for rotating the said shaft, a gear loosely fitted on the said shaft and provided with a sleeved extension, a combined actuating and locking member carried by the said shaft and adapted to cooperate with the said sleeve and casing for preventing 105 rotation of the said gear, means for normally holding the locking member in locking engagement with said casing, said locking member being shiftable by the said shaft incident to rotation thereof to cause disengagement of said locking member from the casing and subsequently establishing driving relation through the locking member between the said shaft and said gear extension.

2. In a combined window regulator and 110 locking device, a casing, adapted to be secured to the window support, a shaft journaled in the casing, a handle for rotating the said shaft, a gear loosely fitted on the said shaft and provided with a sleeved extension,

a cam member provided with a channel on one face and splined to the said sleeved extension, said cam member being loosely carried by the said shaft, lateral extensions on said shaft projecting into the channel in the cam and adapted to establish driving relation between the shaft and the gear through the cam member, and an arcuate member interposed between the said cam and said casing and engaging the said shaft extensions, said arcuate member having means adapted to be wedged securely against the casing by the cam, thereby preventing further rotation of the gear, and being shiftable by the said shaft extensions to cause release of said cam member to permit rotation of the said cam member by said shaft extensions.

In testimony whereof I affix my signature.
EDMOND ETORÉ.
